UNITED STATES PATENT OFFICE.

GUSTAVUS L. STUEBNER, OF FLUSHING, NEW YORK.

DUMPING-BUCKET WITH AUTOMATIC LOCKING-BAIL.

1,202,239.

Specification of Letters Patent. Patented Oct. 24, 1916.

Application filed January 22, 1916. Serial No. 73,508.

To all whom it may concern:

Be it known that I, GUSTAVUS L. STUEBNER, a citizen of the United States, and a resident of Flushing, in the county of 5 Queens and State of New York, have invented certain new and useful Improvements in Dumping-Buckets with Automatic Locking-Bails, of which the following is a specification.

10 This invention relates to a dumping bucket with an automatic locking bail.

In the accompanying drawings Figure 1 represents a side elevation of an exemplification of the invention with the bucket in its 15 normal position; Fig. 2 shows a top plan view of the bucket shown in Fig. 1; Fig. 3 is an elevation of the bucket in its dumping position with a slight modification; Fig. 4 shows a left hand side view of Fig. 3; and 20 Fig. 5 is a top plan view of the bail shown in Fig. 4.

The body of the bucket is indicated in its entirety by the numeral 20, and comprises the side walls 21, rear wall 22, inclined front 25 wall 23 and bottom 24. A reinforcing band 30 is fastened to the upper edges of the body of the bucket. Reinforcing bands 31 are secured to the rear ends of the side walls 21, and reinforcing bands 32 are fastened 30 to the lower ends of said side walls 21. To the rear wall 22 is fastened the bracket 33 for a dumping rope 34. Stationary axles are indicated at 35 and which extend through the triangular protecting hoods 36, 35 the latter being fastened to the upper face 40 of the bottom 24. Semi-cylindrical protecting hoods 38 are fastened to the bottom 24 at the opposite ends of the protecting hoods 36. Wheels 40 are journaled on the axles 35 and are located within the protecting hoods 38. Each of the axles 35 has a split pin 41 extending through the ends thereof and a tap screw 42 extends through the eye of said split pins and is in threaded engagement with a reinforcing plate 43 secured to its accompanying reinforcing band 32. Angle stop plates 45 are fastened to the side walls 21 of the body of the bucket. Reinforcing plates 46 are fastened to the inner 50 faces of the side walls 21 of the bucket and trunnion plates 47 with the trunnions 48 are fastened to the outer faces of the side walls 21 opposite the plates 46.

The invention is shown with two bails, one 55 of which I designate a charging bail with its side view shown in Fig. 1 and the other a

dumping bail shown with its side view in Fig. 3, while the front view of both bails is shown in Fig. 4. The charging bail comprises a rear plate with the wings 50, 51, 52 60 and 53 and the dumping bail contains the wings 50, 51, the wings 52, 53 being omitted in the latter bail, otherwise both of the bails are of similar construction. The rear plate with the four wings has extending 65 therefrom the stop bars 54 and 55, and the rear plate with the two wings has only the stop bar 54. Each of the rear plates has a vertical guide slot 56 which terminates in a divergent guide opening 57. Positioning 70 handles 58, 59 extend respectively from the wings 50, 52. A front plate 60 is shown with a similar vertical guide slot 56 and divergent opening 57. Between the rear and front plates are fastened the vertical legs 75 63 of the bails. The latter are connected by horizontal members 64. A strap 65 extends from the horizontal member 64. A hook 70 with the nose 76 is pivoted between said rear and front plates on the pin 71, and has 80 formed therewith the lower inclined guide edge 72 and lug 73. A stop block 74 and a filling block 75 are located between said rear and front plates. To the vertical legs 63 of the bail are fastened the hinge brackets 85 80, and in the latter are pivoted the bell 80 cranks with the arms 81 and 82. A stop lug 83 extends from each bell crank. A pair of links 85 connect each arm 82 with its accompanying lug 73. The arms 82 of the bell 90 cranks are connected by the operating handle 86. A hoisting hook 90 is suspended from the hoisting chain 91 and engages the strap 65 at both the charging and dumping station for the bucket 20. Tracks 95 are 95 shown for the wheels 40 of the bucket to roll on.

To use the dumping bucket attention is directed to Fig. 1 in which the bail is shown locked with the bucket. Previous to the 100 locking of the bail with the bucket, the latter is filled with its load, which is generally at a point distant from the charging bail. The bail is always suspended on the hook 90. The bucket can be moved to its proper position for hoisting by means of the tracks 95. After the bucket has been located in proper position the bail is lowered in place and locked with the trunnions 48. As the bail is lowered in place the lower inclined 105 guide edges 72 of the hooks 70 bear against the said trunnions 48 and swing in the di-

rection of the arrow "A" until the nose 76 of each hook 70 is moved out of the path of its trunnion 48. Then the hooks 70 will become locked with the trunnions 48 by 5 gravity, in other words the bail will be automatically locked with the bucket 20. The operator then raises the bucket by means of the bail and hoisting chain. The bucket can then be placed on a vehicle or other appurtenance and the bail detached therefrom. The latter operation is performed by lowering the bail until the stop bars 54 and 55 bear upon the angle stop plates 45, and then the operating handle 86 is moved in 10 the direction of the arrow "B" by which the hooks 70 will become disengaged from the trunnions 48. The bucket is now brought to the dumping station and the bail shown in Figs. 3 and 4 is locked with the trunnions 48. 15 Next the bucket is raised by means of the hoisting chain 91, the dumping rope 34 maintained slack until the bucket is to be dumped. To perform the latter operation the dumping rope 34 is pulled up, which 20 dumps the bucket as shown in Fig. 3. The elimination of the wings 52 and 53 of the bail allows the bucket 20 to take the position shown in Fig. 3, and the wings 50 with the stop bars 54 prevent the bucket turning turtle when dumping by reason of the 25 said stop bars contacting with the pair of angle stop plates 45 at the front end of the bucket.

Referring to Fig. 1 the coaction of the 30 stop bars 54, 55 respectively with the angle stop plates 45, prevents the bucket from being tipped or dumped, when being raised, in case it should strike some object.

Having fully described my invention 35 what I desire to secure by Letters Patent and claim is:

1. The combination in a bucket of trunnions, an automatic locking and detachable bail for the bucket to engage said trunnions 45 and hooks with guide edges bearing against the trunnions when the bail is lowered in place and thereby said hooks swinging out of the path of the trunnions when the bail is lowered in place, the said hooks subsequently locking with the trunnions by gravity.

2. The combination in a bucket of trunnions, an automatic locking and detachable bail for the bucket having a pair of guide 55 slots to engage said trunnions, hooks with lower inclined guide edges bearing against the trunnions when the bail is lowered in place and thereby swinging said hooks out of the path of the trunnions when said bail 60 is lowered in place, the said hooks subsequently locking with the trunnions by gravity and means to unlock the hooks from the trunnions.

3. The combination in a bucket of trunnions extending therefrom, stop plates ex-

tending from the bucket, an automatic locking bail with guide slots for the bucket, stop bars on the bail to contact with the said stop plates, a hook pivoted on each side of the bail opposite said guide slots and having 70 inclined guide edges, said inclined guide edges bearing against said trunnions when the bail is lowered in place, and thereby swinging the said hooks out of the path of the trunnions when said bail is lowered in 75 place, the said hooks subsequently locking with the trunnions by gravity, a link with one end pivoted to each hook and means to raise the links and thereby unlock the hooks from the trunnions.

4. The combination in a bucket of trunnions therefor, stop plates extending from the bucket, an automatic locking bail with guide slots for the bucket, stop bars on the bail to contact with the said stop plates, a 80 hook pivoted on each side of the bail opposite said guide slots and having inclined guide edges bearing against the trunnions when the bail is lowered in position and thereby swinging the said hooks out of the 85 path of the trunnions when the bail is lowered in place, the said hooks subsequently locking with the trunnions by gravity, a link with one end pivoted to each hook, a 90 pair of bell cranks pivoted to the bail, the other end of each link pivoted to one of said bell cranks and an operating handle for the 95 said bell cranks.

5. The combination in a bucket of trunnions extending from the sides thereof, an 100 automatic locking bail for the said trunnions, means to unlock the bail from the said trunnions, wheels journaled in the bucket, means to dump the bucket and means on the bucket coacting with the bail to prevent tipping said bucket before being dumped.

6. The combination in a bucket of trunnions therefor, an automatic locking bail for said bucket, means on the bail to position 110 the same to lock with the trunnions of the bucket, means to unlock the bail from said trunnions and means to connect a dumping rope to the bucket.

7. The combination in a bucket of trunnions therefor, an automatic locking charging bail for said bucket, means to prevent the tipping of the bucket when the said charging bail is locked thereto, an automatic 115 locking dumping bail for the bucket and means to dump the bucket with the latter bail.

8. The combination in a bucket of trunnions therefor, an automatic locking and charging bail for the said bucket, means on 120 the bail to prevent the tipping of the bucket when the said charging bail is locked to the trunnions thereof, an automatic dumping bail for the bucket, means to dump the 125 bucket with the latter bail, and means in 130

the latter bail to prevent the bucket turning turtle.

9. The combination in a bucket of trunnions therefor, an automatic locking and charging bail to lock with said trunnions, wings with stop bars on the bail to prevent the bucket tipping when being charged, an automatic locking dumping bail for the bucket, wings with stop bars on the latter bail to prevent the bucket turning turtle and

means to dump the bucket with the latter bail.

Signed at Long Island City in the county of Queens and State of New York this 20th day of January A. D. 1916.

GUSTAVUS L. STUEBNER.
